ELECTRIC SWITCH

Leslie A. Kempton, Chicago, Ill., assignor to
 Edison General Electric Appliance Company,
 Inc., Chicago, Ill., a corporation of New York

Application September 28, 1940, Serial No. 358,860

5 Claims. (Cl. 200—6)

This invention relates to electric switches and more particularly to multiple-position electric switches and has for its object the provision of an improved device of this character which can be manufactured at low cost.

In multiple-position electric switches it is customary to provide special contact means formed of material capable of resisting pitting by the arcs formed upon the making or breaking of the circuit being controlled. In many instances the contact means is in the form of contact buttons made of silver which is known to have the desirable arc resisting properties. Such special contact means, and especially those in the form of precious metal contact buttons, usually represent a large proportion of the cost of a particular switch and this is especially true in multiple-position switches which are used for domestic cooking appliances. Thus if the number of such special contact means required for a particular multiposition switch could be reduced a substantial saving in the cost of the switch could be made.

It is the specific object of this invention to provide a new and improved multiple-position switch in which the number of special arc resisting contacts used may be substantially reduced without affecting the number of control positions of the switch. Expressed differently, it is the specific object of this invention to provide a multiple-position control switch with a reduced number of special arcing contacts and with means for controlling the sequence of operation of the contacts so that when the switch is moved to its different circuit controlling positions the various circuits will be made or broken at the arcing contacts provided.

While not limited thereto, this invention is particularly applicable to multiple-position switches of the type described and claimed in United States Patent 2,203,236, issued June 4, 1940, on an application filed by Charles P. Randolph and me and assigned to the assignee of the present invention. While such multiple-position switches have many uses, they are particularly applicable for controlling electric range heating circuits as described in the aforementioned patent. In accordance with this invention there is provided in a switch of this type a plurality of arcing contacts made of suitable arc resisting material such as silver, and a plurality of non-arching or circuit changing contacts made of a suitable base metal capable of carrying the load current. Included with this contact construction is new and improved means for controlling the sequence of

operation of the contacts so that the load circuits are always made or broken at the arcing contacts as will more fully appear hereinafter.

For a more complete understanding of this invention reference should be had to the accompanying drawings in which Fig. 1 is a front elevation of an electric switch embodying my invention; Fig. 2 is a rear elevation of the switch shown in Fig. 1 with a part removed so as to illustrate certain details of the construction; Fig. 3 is a sectional view taken on the line 3—3 of Fig. 2 and looking in the direction of the arrows, the switch of Fig. 3 being shown mounted on a supporting panel; Fig. 4 is a partial sectional view taken on the line 4—4 of Fig. 2 looking in the direction of the arrows, showing details of the contact structure of this invention; Fig. 5 is a view taken on the line 5—5 of Fig. 3 looking in the direction of the arrows, parts being removed to show details of the cam construction; Figs. 6 and 7 are developed sectional views taken on the lines 6—6 and 7—7 respectively of Fig. 5, looking in the direction of the arrows and showing details of related portions of the cam construction; Fig. 8 is a view similar to Fig. 4 showing a modified form of contact structure; Fig. 9 is a perspective view showing additional details of the modified form of contact structure shown in Fig. 8; Figs. 10—15, inclusive, are diagrammatic representations of the switch shown in Figs. 1—7 showing the switch controlling a heating element having two resistances to provide various degrees of heat; and Figs. 16—21, inclusive, are sectional views taken on the lines 16—16 through 21—21 of Figs. 10—15 respectively showing the position of the contact members in each position of the cam member illustrated in Figs. 10—15.

Referring to the drawings, my invention has been shown in one form as applied to a multi-pole switch intended to control the heating circuit of a surface unit of an electric range. As illustrated in Figs. 1—3, this switch comprises a supporting panel 10 formed of some suitable insulating material such as a phenol condensation product. This supporting panel is provided with a peripheral flange 11 which defines a rectangular-shaped chamber 12. Mounted within the chamber at one end thereof, the lower end as viewed in Fig. 2, and secured to the panel by means of rivets is a series of line terminals 13, 14 and 15. The horizontal portions of these terminals extend along the lower end of the chamber 12 and are provided with pairs of contacts 16 and 17, 18 and 19, and 20 and 21, re-

spectively, which will be described more fully hereinafter. The vertical portion of the line terminals **13**—**15** projects beyond the lower wall of the chamber so that connections can be made exteriorly of the chamber with a suitable source of supply (not shown). In order to facilitate making electrical connections, the terminal members **13**, **14** and **15** are suitably bent so that the ends thereof lie in different planes, as shown in Fig. 3. Molded in the upper flange surface of the supporting panel is a plurality of openings **22** in each of which is provided a load terminal screw **23** which is secured in position by means of a nut **24** and to which is adapted to be connected the load being controlled.

Secured to the upper end of the chamber **12** by means of rivets **25** is a plurality of contact fingers **26**—**31**, inclusive, which are made of a suitable resilient, electrically conducting material, such as phosphor bronze, and are interposed between the line terminals **13**, **14** and **15** and the load terminals **23** to control the transfer of power therebetween. Referring to Fig. 2, it will be observed that the contact finger **26** is provided with a portion **32** which projects through the top wall of the chamber and terminates under the extreme right terminal screw **23**, as viewed in Fig. 1, to form an electrical connection between the screw and the main portion of the contact finger **26**. The contact fingers **27** and **28**, on the other hand, are formed from a single strip of material and the fingers are in effect legs of a substantially U-shaped strip having a bridging portion **33**. Projecting outwardly from the bridging portion, in line with the contact finger **28** is a portion **34** which is fastened under the second terminal screw **23** from the right, as viewed in Fig. 1, to form an electrical connection between this load terminal and the contact fingers **27** and **28**. The contact fingers **29** and **30** are similarly formed from a single piece of substantially U-shaped material which also is provided with a portion **35** which extends outwardly through the top wall of the chamber and is fastened under the third terminal screw from the right, as viewed in Fig. 1, to form the electrical connection between the contact fingers **29** and **30** and the terminal screw **23**. The contact finger **31** is similar to the finger **26** and is provided with a portion **36** which extends outwardly through the top wall of the chamber and is fastened under the extreme left-hand terminal **23** viewed in Fig. 1 to form an electrical connection therewith. In order to maintain the various terminal fingers in their relatively spaced positions, a plurality of bosses **37** are molded in the bottom wall of the chamber **12** so as to lie between adjacent contact fingers.

In order to provide an electrical connection between the contact finger **31** and the pair of fingers **27** and **28**, there is provided a U-shaped shunt strip **38** made of a suitable conducting material. The legs of this shunt strip are secured under the nuts **24** of the terminal members **23** so that the shunt is spaced from the contact fingers and lies near the top of the chamber **12**, as shown in Fig. 3. Moreover, as shown in Fig. 3, the chamber **12** is closed by a cover **12a** formed by a plate of suitable electrically insulating material which is secured to the panel **10** by means of rivets or some other suitable fastening means.

In order that the contact fingers may perform their circuit controlling and circuit changing functions effectively, each finger is provided with a contact which cooperates with a corresponding

contact provided on the line terminal members **13**—**15**. In the usual switch construction, both the line contacts and the contacts on the fingers are made of a suitable material capable of withstanding the arcs which occur upon the making or breaking of the load circuit. Contacts made of silver are usually employed because they have been found to have the desirable arc-resisting properties. Such silver contacts usually constitute the most expensive single item in a multi-position switch construction and greatly influence the cost of the switch. Therefore, if it is possible to effect a reduction in the number of these silver contacts required without affecting the life or reliability of the switch, the cost of a switch can be materially reduced.

In accordance with this invention, I have provided a new and improved switch construction by which such a reduction in silver contacts can be effected. Considered generally I have provided a multi-position multi-pole switch in which only a certain number of contacts are made from arc-resisting materials, such as silver and the like, and these are termed arcing contacts. The remainder of the contacts are made of a base material capable of carrying the load current and are termed non-arching contacts. The sequence of operation of these contacts is then controlled by a new and improved cam member so that the circuits being controlled are made and broken at the arcing contacts whereas the non-arching contacts serve merely as circuit changing contacts. In other words, I have provided in conjunction with my improved contact arrangement, new and improved means for controlling the sequence of operation of the contacts so that upon the making of the various circuits controlled by the multi-position switch, the arcing contacts, i. e., those made of a material capable of withstanding the arc generated, are closed after the non-arching or circuit changing contacts are closed, and, upon the breaking of the various circuits, the arcing contacts are opened before opening of the non-arching contacts.

Turning now to the specific embodiment of my invention shown in the drawings and referring to Fig. 4, it will be observed that the terminal member **13** is provided with a pair of arc-resisting contact abutments. In the preferred form of this invention, these abutments, as well as the remainder of the arc-resisting abutments to be described hereinafter, are in the form of silver contact buttons. If desired, however, these silver contact buttons could be replaced by a silver inlay or a heavy silver plate direct on the contact fingers or by suitable non-metallic arc-resisting abutments such as carbon contact buttons. Arranged to cooperate with the silver contact buttons on the terminal member **13** is a pair of silver contact buttons **39** and **40** which are welded or otherwise secured to the contact fingers **26** and **27**, respectively. In addition to these pairs of arcing contacts, there is one other pair of arcing contacts which are likewise formed by silver contact buttons. This pair consists of the silver contact button **20** which is secured to the terminal member **15** and the silver contact button **41** which is mounted on the contact finger **30**.

The remaining pairs of contacts are, in accordance with this invention, made from a material which is capable of carrying the load current of the circuit being controlled by the switch. These contacts can, therefore, be made from a base material such as phosphor bronze and as shown in Fig. 4 they are preferably formed by

pressing integral bosses 18, 19 and 21 in the line terminals 14 and 15 against which the end of the contact fingers 28, 29 and 31 are adapted to bear to form pairs of contacts 18-28, 19-29 and 21-31, respectively. These pairs of contacts may be designated the non-arching or circuit changing contacts since the only function they serve in the switch is to vary the circuit relations of the circuits controlled by the switch. In order to protect the non-arching contact members from oxidation and corrosion during use, it has been found desirable to provide on these contacts a light silver flash or coating. However, it is to be understood that such a coating is merely provided to increase the life of the switch as a whole and may be omitted without affecting the operation of the switch.

In order that the travel of the non-arching contacts between their opened and closed positions may be the same as the travel of the arcing contacts, the entire horizontal portion of the terminal member 14 and the portion of the terminal member 15 in which is formed the non-arching contact 21 are offset as shown in Figs. 2 and 4 to bring the non-arching contacts provided in the terminal closer to the contact fingers 28, 29 and 31. In Figs. 8 and 9 I have shown a modified form of non-arching contact structure which may be employed. In this modified form it is possible to arrange the horizontal portions of the terminal members 13, 14 and 15 in a line as shown in Fig. 8. This is made possible by forming in the end of the terminal members 28, 29 and 31 substantially cylindrical bosses 42, 43 and 44 which cooperate, respectively, with the bosses 18, 19 and 21 provided in the terminal members 14 and 15.

As shown in Fig. 4, the contacts of the multi-position switch have a normally opened position and are moved to the closed position upon the movement of the contact fingers 26-31. Provided in a series of horizontally aligned apertures in the panel 10 is a series of pins 45-50. These pins, when forced inwardly or to the right as shown in Fig. 3, engage the fingers 26-31, respectively, to move them outwardly in a direction to cause the contacts mounted thereon to engage the respective contacts on the line terminals 13-15. The movement of the pins 45-50 is controlled by a cam 51 which preferably is in the form of a flat disk-like metallic member although this cam may be made from any other suitable material.

In order to control the sequence of operation of the pins 45-50 so that the circuit connection between the line and load terminals of the switch will be made at the arcing contacts after closing of the circuit changing contacts and will be broken at the arcing contacts before opening of the circuit changing contacts, there is formed in the cam 51 a series of arcuate depressions which lie in radial spaced relation so that one depression or group of depressions is provided for controlling each of the actuating pins in the switch. Referring to Fig. 5, it will be observed that the pin 50 for actuating the contact finger 31 is controlled by the outermost arcuate depression 52 which is broken by a single flat surface 53; that the pin 45 for actuating the contact finger 26 is controlled by a group of radially aligned arcuate depressions 54-58 which are separated by a plurality of flat surfaces 59-63; that the pin 49 for actuating the contact finger 30 is controlled by the arcuate depression 64 which is broken by a single flat surface 65; that the pin 46 for ac-

tuating the contact finger 27 is controlled by the arcuate depression 66 which is separated by a single flat surface 67; that the pin 48 for actuating the contact finger 29 is controlled by the arcuate depression 68 which is separated by the single elongated flat surface 69; and that the pin 47 for actuating the contact finger 28 is controlled by the arcuate depression 70 which is separated by a single flat surface 71. The length of the arcuate depressions and the relative position of the flat surfaces which separate these depressions is designed so that, in operating the switch, at least one of the pins 45, 46 and 49 for the contact fingers 26, 27 and 30, respectively, will be actuated to close one pair of arcing contacts after the pins 47, 48 and 50 for the contact fingers 28, 29 and 31, respectively, have been actuated to close the non-arching contacts upon the making of a particular circuit and at least one of the pins 45, 46 and 49 will be actuated prior to movement of any of the pins 47, 48 and 50 to open the arcing contacts ahead of the non-arching contacts upon breaking of a particular circuit. In other words, the cam surface is so developed that the contact fingers 26, 27 and 30 will be the last to be moved when a circuit is being made and first to be moved when a circuit is being broken.

It is to be particularly noted as shown in Fig. 30 that the means for operating the contact finger 26 comprises a series of arcuate depressions which are separated by flat portions whereas the means for operating the remaining contact fingers comprises a single arcuate depression which is separated by a single flat portion. Thus it will be observed that the contact finger 26 which is one of those provided with precious metal contacts will be operated in every position of the switch either to make or break the load circuit.

As has already been pointed out, the pins 45, 46 and 49 control the contact fingers which operate the arcing contacts of the switch whereas the pins 47, 48 and 50 control the contact fingers which operate the circuit changing contacts for the switch. In order to insure that as the switch is moved from one position to another the arcing contacts will be operated in their proper sequence relative to the non-arching contacts, the flat surfaces of the cam over which the pin for operating the non-arching contacts must pass is made longer than the flat surfaces over which the pins for the arcing contacts must pass. The details of this construction are clearly shown in the developed sectional views shown in Figs. 6 and 7.

Referring to these views, it will be observed that the flat surfaces 69 over which the pin for the non-arching contact 29 passes begins well in advance of the flat surface 59 over which the pin for arcing contact 26 passes and terminates well beyond the end of the flat surface 60 over which the pin for the arcing contact 26 passes. By this construction it is positively assured that the non-arching contacts will be moved before the arcing contacts upon circuit making and after the arcing contacts upon circuit break. It will, of course, be understood that the relation shown in Figs. 6 and 7 obtains for the remaining arcing and non-arching contact means.

As is clearly shown in Fig. 3, the cam 51 is rigidly secured to an operating shaft 72 which is journaled at its inner end in a bearing 73 provided for it in the panel 19 and at its outer end in a bearing 74 provided for it in a cup-shaped cover member 75 which houses or encloses the cam. In order to secure the housing

75 to the panel 19, there is provided on the edge of its side wall a pair of oppositely spaced fingers 76 which are secured to the panel by means of rivets 71.

In order to hold the cam 46 in any particular selected controlling position, a positioning member 18 is provided which is secured to the shaft 72 by means of a splined connection (not shown). This positioning member has a series of flat faces 79 as shown in Fig. 1, the number of faces provided depending upon the number of controlling positions of the switch. In the specific switch shown in Figs. 1-3, it is contemplated that the switch will have six controlling positions and hence the positioning member is provided with an equal number of faces 79, the cam being preferably formed as a hexagon so that the faces have an equal length and so that the controlling positions are substantially 60 degrees apart. Mounted on opposite sides of the positioning cam is a pair of flat springs 80 which at their opposite ends are secured to opposite sides of the housing 75, as shown in Figs. 1-3. For this purpose the springs 80 are provided at their ends with extensions 81 which are directed through apertures provided for them in the housing. The upper and lower ends of the springs, as shown in Fig. 1, are spaced sufficiently close together so that the central sections of the springs are pressed against the sides of the positioning member thereby to hold it resiliently in any controlling position to which it is moved.

When the switch is used to control the surface unit of an electric range, it will normally be mounted on a panel 32 at the front of the range so that the shaft 72 extends outwardly therefrom. Mounted on the projecting end of this shaft is a knob 83 by which the switch may be readily operated to its various circuit controlling positions. As shown, the knob may have a substantially triangular shape in order to provide a visible indication of the circuit controlling position of the switch. In practice, the casing 75 of the switch is used for mounting the switch on a panel 32 and for this purpose it is provided with a pair of threaded apertures into which screws 84 are threaded as clearly shown in Fig. 3.

The switch of Figs. 1-7 is diagrammatically shown in Figs. 10-15 as controlling the energization of a heating unit, such as the surface unit of an electric range, having two resistance elements 85 and 86 which are energized from a suitable source of supply. As shown in Figs. 10-15, the unit is connected through the switch to a three-wire supply source 87, 88 and 89 which provides two different voltages which may be impressed on the heating unit. The wires 87 and 88 are outside wires of this source while the wire 89 is the neutral and the voltage between the two outside wires is substantially twice the voltage between any one outside wire and the neutral. As shown, the outside or left-hand end of the resistance 85 is connected through a load terminal to conducting strips 34 and 38 and the outside end of the resistance 86 is connected through a load terminal to the strip 32. The opposite ends of the units 85 and 86 are connected together and the common connection is connected through a load terminal to the conducting strip 35. The three line terminals 13-15 and their corresponding pairs of contacts are connected as shown to the three wires 87-89 respectively.

In considering the operation of my improved multi-position switch reference will be had to

Figs. 10-15 which diagrammatically show each circuit controlling position of my improved multi-position switch and to Figs. 16-21 which are sectional views through the pin actuators showing the position of the cover, pins and contacts of the switch for each circuit condition diagrammatically represented in Figs. 10-15 respectively.

Referring first to Figs. 10 and 16, these views show the "off" position of the switch. It will be observed that the pins 45-50 are each located in their respective depressions in the cam so that they are in their retracted position. Thus all of the switch contacts are in their normally open position and no energy is transferred from the line to the load. It will be noted that in this position the heating elements 85 and 86 are completely isolated from the power supply conductors because of the multi-pole switching arrangement. This is a desirable feature and is often required for safety purposes.

Assuming now that the knob 83 is rotated clockwise from the position shown in Fig. 1 to the next succeeding indexed position, the cam 51 will be rotated clockwise through approximately 60 degrees to the position shown in Fig. 11. In this movement of the cam the pins 47, 49 and 50 for the contact fingers 28, 30 and 31 remain in their retracted position. However, during the first part of this movement, the pin 48 of the contact finger 29 moves out of its depression 68 and up onto the flat surface 69 so that the non-arcing contacts 19 and 29 are closed. As the movement continues, the pin 46 for the contact finger 27 moves out of its depression 66 and onto the flat surface 67 so that the arcing contacts 17 and 40 are closed and the pin 45 for the finger 26 moves out of the depression 54 and onto the flat surface 59 so that the arcing contacts 16 and 39 are closed. The position of the contacts in this position of the cam is shown in detail in Fig. 17. With the contacts in the position illustrated it will be apparent from Fig. 11 that the two heating elements 85 and 86 are placed in parallel across the outside wires 87 and 88 so that a maximum heat output is obtained. This position of the switch is termed the "high heat" or "speed" position.

Assume now that the switch is turned to its next indexed position which corresponds to a rotation of the knob 83 and the cam 51 clockwise through an additional 60 degrees. In the first part of this movement the actuating pin 45 for the contact finger 26 moves off the flat surface 59 and into the next succeeding depression 55 causing the arcing contacts 16 and 39 to be opened, thus opening the circuit of the heating element 86. As this clockwise movement increases, the operating pin 46 of the contact finger 27 moves off of the flat surface 67 and into the depression 68 causing the arcing contacts 17 and 40 to be opened to open the circuit of the heating element 85. As the movement continues further, the pin 45 will move out of the depression 55 and onto the second flat surface 60, thus causing the arcing contacts 16 and 39 to be closed again. It will be observed that in this entire movement the actuating pin 48 of the contact finger 29 has remained on the flat surface 69 so that the non-arcing contacts 19 and 29 remain closed during the switching movement as is clearly shown in Fig. 6. With the contacts 19 and 29, 16 and 39 closed as shown in Fig. 18, the heating element 86 alone is connected across the outside wires 87 and 88 as is clearly shown in Fig. 12 to produce the "half speed" position of the switch.

Assume now that the switch is advanced from the "half speed" position to the next succeeding indexed position which corresponds to moving the cam 51 through an additional 60 degrees. In this movement the first operation which takes place is that the pin 45 for the contact finger 26 moves off the flat surface 60 and into the next succeeding depression 56 to cause the circuit for the heating element 85 to be opened. After the pin 45 has moved into the depression 56 and as the movement further continues, the operating pin 48 for the contact finger 29 moves off the flat surface 69 and into the depression 68 to cause the non-arching contacts 19 and 29 to be opened and simultaneously the operating pin 47 for the contact finger 28 moves out of the depression 70 and onto the flat surface 71 to cause the non-arching contacts 18 and 28 to be closed. Upon the final movement of the cam to this third position, the pin 45 for the contact finger 26 moves out of the depression 56 and onto the flat surface 61 to cause the arcing contacts 16 and 39 to be closed. With the contacts 18 and 42 and 16 and 39 closed as shown in Fig. 19, it will be observed from Fig. 13 that the heating elements 85 and 86 are placed in series across the outside wires 87 and 88 to produce a "quarter heat" position of the switch.

Assume now that the switch is advanced from the "quarter heat" position to the next succeeding indexed position which corresponds to a rotation of the knob 83 and the cam 51 through an additional 60° or through an angle 240 degrees from the "off" position shown in Fig. 10. In the first part of this movement the pin 45 for the contact finger 26 moves off the flat surface 61 and into the depression 57 to cause opening of the arcing contacts 16 and 39 thereby opening the heating circuit of the series connected elements 85 and 86. As the movement continues, the pin 47 for the contact finger 28 moves off the flat surface 71 and into the depression 70 to cause opening of the non-arching contacts 18 and 28. As the movement advances still further, the pin 49 for the contact finger 30 moves out of the depression 64 and onto the flat surface 65 to cause closing of the arcing contacts 20 and 41 and the pin 45 for the contact finger 26 moves out of the depression 57 and onto the flat surface 62 to cause closing of the arcing contacts 16 and 39. With the contacts 16 and 39 and the contacts 20 and 41 closed as shown in Fig. 20, it will be observed from Fig. 14 that the heating element 86 is now connected across the outside wire 87 and the neutral wire 89 and is thus energized at substantially half the voltage between the two outside wires so as to produce the "thrift heat" position of the switch.

Assume now that the switch is advanced from the "thrift" position to its next succeeding indexed position which corresponds to rotation of the knob 83 and cams 51 through an additional angle of 60 degrees. In the first part of this advance the pin 45 for the contact finger 26 moves off the flat surface 62 and into the next succeeding depression 57 to open the arcing contacts 16 and 39. As the movement continues, the pin 49 for the contact finger 30 moves off the flattened portion 65 and into the depression 64 to cause opening of the arcing contacts 41 and 20. Upon a still further advance, the pin 50 for the contact finger 31 moves out of the depression 52 and into engagement with the flattened surface 53 to cause closing of the non-arching contacts 21 and 31 and subsequently the pin 45 for the contact finger 26

moves out of the depression 58 and onto the flat surface 63 to cause closing of the arcing contacts 16 and 39. With these pairs of contacts closed as shown in Fig. 21 it will be observed from Fig. 5 that the heating elements 85 and 86 are connected in series across the outside wire 87 and the neutral wire 89 to produce the lowest heat output for the circuit which is termed the "warm" position of the switch.

10 By advancing the switch to the next indexed position the knob cam will have been rotated through 360 degrees and hence will be in return the "off" position shown in Fig. 10. In the first part of this movement to the "off" position, the pin 45 for the contact finger 26 will move off the flattened surface 63 and into the depression 54 to cause opening of the contacts 16 and 39. Then as the advancing movement continues, the pin 50 for the contact finger 31 will move off the flattened surface 53 and into the depression 52 to cause opening of the non-arching contacts 21 and 31.

Through all of the above multi-pole switching and circuit changing operations as the switch is moved through its six positions, it will be observed that in every instance the non-arching contacts are closed before the arcing contacts upon the making of a circuit and the arcing contacts are opened before the non-arching contacts 25 upon the breaking of a circuit. Thus any arcing which occurs upon the closing or opening of the circuit will take place at the silver arcing contacts and the base metal non-arching contacts serve merely as circuit changing contacts.

30 35 From the foregoing detailed description it will be observed that I have provided a new and improved multiple-positioned switch construction which can be manufactured at low cost, the salient cost reduction being produced by so 40 constructing and arranging the switch that the number of precious metal contacts used therein may be substantially reduced and in the case of a six-position switch may be reduced by half.

While I have shown and described a particular embodiment of my invention, it will be understood, of course, that I do not intend to be limited thereto since many modifications can be made. I, therefore, contemplate by the appended claims to cover all such modifications as fall 50 within the true spirit and scope of my invention.

What I claim as new and desire to secure by Letters Patent of the United States is:

1. A multi-position multi-pole switch comprising an insulating supporting panel, a plurality of resilient contact fingers mounted on said panel, a plurality of pairs of relatively movable contacts comprising relatively fixed contacts mounted on said panel and relatively movable contacts carried by said contact fingers, said pairs of contacts including at least one pair of arcing contacts and at least one pair of non-arching contacts, means comprising a rotary operating cam having cam surfaces for actuating said fingers to close said pairs of contacts when said cam is rotated, said cam having at least one switch closing position in which a plurality of pairs of said contacts including at least one pair of arcing contacts and one pair of non-arching contacts are closed to effect a multi-pole switching function, said cam surfaces being arranged so that upon movement of said cam to said switch closing position the arcing contacts are closed subsequent to the non-arching contacts and upon movement of said cam from said 60 65 70 75 switch closing position said arcing contacts are

opened prior to said non-arching contacts whereby arcing occurs only at said arcing contacts.

2. A multi-position multi-pole switch comprising an insulating supporting panel, a plurality of normally open pairs of relatively movable contacts mounted on said panel, said pairs of contacts comprising pairs of non-arching contacts and a pair of arcing contacts, and means comprising a rotary cam having cam surfaces for effecting a closure of said pair of arcing contacts and different pairs of said non-arching contacts when said cam is rotated to a plurality of switch closing positions to effect a different multi-pole switching function in each switch closing position, said cam surfaces being arranged so that when said cam is rotated away from any one of said switch closing positions said arcing contacts are opened prior to said non-arching contacts whereby arcing occurs only at said arcing contacts.

3. A multi-position multi-pole switch comprising an insulating supporting panel, a plurality of pairs of relatively movable normally open contacts mounted on said panel, said pairs of contacts including at least one pair of non-arching contacts and at least one pair of arcing contacts, means comprising a single movably mounted cam member for closing all of said pairs of contacts, said cam member having at least one switch closing position in which a plurality of said pairs of contacts including a pair of non-arching and a pair of arcing contacts are closed to effect a multi-pole switching function, said cam member being shaped so that upon a movement of said cam member to said switch closing position the arcing contacts are closed subsequent to the non-arching contacts and upon a movement of said cam from said switch closing position said arcing contacts are opened prior to said non-arching contacts whereby arcing occurs only at said arcing contacts and

only said arcing contacts need be formed of arc resistant material.

4. A multi-position multi-pole switch comprising an insulating supporting panel, a plurality of pairs of relatively movable contacts mounted on said panel, said pairs of contacts including at least one pair of non-arching contacts and at least one pair of arcing contacts, a single movably mounted cam member for actuating all of said contacts, said cam member being movable to a switch opening position in which said pairs of contacts are open and to at least one switch closing position in which a pair of non-arching and a pair of arcing contacts are closed to effect a multi-pole switching function, said cam member being shaped so that upon a movement of said cam member to said switch closing position the arcing contacts are closed subsequent to the non-arching contacts whereby arcs formed upon the closing of said contacts are dissipated at said arcing contacts.

5. A multi-position multi-pole switch comprising an insulating supporting panel, a plurality of pairs of relatively movable contacts mounted on said panel, said pairs of contacts including at least one pair of non-arching contacts and at least one pair of arcing contacts, a single movably mounted cam member for actuating all of said pairs of contacts, said cam member being movable to a switch opening position in which said pairs of contacts are open and to at least one switch closing position in which a pair of non-arching and a pair of arcing contacts are closed to effect a multi-pole switching function, and said cam member being shaped so that upon a movement of said cam member from said switch closing position said arcing contacts are opened prior to said non-arching contacts whereby arcs formed upon the opening of said contacts are dissipated at said arcing contacts.

LESLIE A. KEMPTON.
